UNITED STATES PATENT OFFICE.

THOMAS F. FITZSIMMONS, OF BROOKLYN, NEW YORK.

MANUFACTURE OF CARBURETED PRODUCER-GAS.

1,164,081.

Specification of Letters Patent. Patented Dec. 14, 1915.

Application filed December 9, 1908. Serial No. 466,682.

To all whom it may concern:

Be it known that I, THOMAS F. FITZSIMMONS, a citizen of the United States of America, and a resident of Brooklyn, New York, have invented a new and useful Manufacture of Carbureted Producer-Gas, which is fully set forth in the following specification.

This invention relates primarily to the production of fixed carbureted producer-gas; also to the carbureting of producer-gas, obtained from higher grade anthracite coal or from inferior grades of anthracite, or from bituminous coal or coke or any carbonaceous fuel. And the invention consists of the process hereinafter set forth and claimed for the manufacture of fixed carbureted producer-gas.

Among the features of the invention are the introduction of the hydrocarbons, in the form of oil spray, into the crude gas at or about a predetermined temperature, and the subsequent subjection of the mixture to still higher temperatures for the purpose of properly carbureting and fixing the gases.

Another feature is the continuous operation of the producer and the utilization of its crude gases first for heating the carbureting-and-fixing-chamber, and subsequently for combining with the oil to produce the carbureted gas.

One feature of my invention is based on the fact that in carbureting gases, there is a certain temperature (or range of temperature) where the oil used for that purpose is most effectively disintegrated or "cracked." At lower temperatures the oil will not be completely or properly "cracked," and the gases will not receive (or retain, during the subsequent "fixing") the full amount of hydrocarbons present in the oil. On the other hand, at higher temperatures there occurs a wasteful destruction of the oil with the production of soot, and with the same ultimate result that the full value of the hydrocarbons is not available in the out-put of fixed carbureted-gas. The most effective temperature for properly cracking the oil is hereinafter termed the "critical temperature."

This temperature varies with the nature of the oil itself, and the proper temperature for each specific oil is known to persons skilled in this art. The expression "critical temperature" as hereinafter used means a range of temperature around that

point, rather than a sharply-defined specific degree of temperature.

Another feature of my invention is based on the facts that carbureted gases can be effectively "fixed" by subjecting the mixture to high temperatures; and that the use, in the "fixing" operation, of temperatures so much higher than the "critical temperature" as to calcine the nascent oil-spray if applied to it, is not only not injurious to the mixture, but is efficient to a remarkable degree in properly fixing the carbureted gases, and yields a larger output of better quality than heretofore obtained by other processes; and that this treatment, applied to a mixture of oil-spray and producer-gas, yields fixed carbureted producer-gas.

The foregoing facts are utilized in the present process by first subjecting the oil-spray, at the time of its introduction into the crude gases, to its "critical temperature," and then subjecting the mixture to gradually increasing temperatures above that critical temperature. Preferably this is accomplished by providing a continuous out-put of the crude gases, and using the first portion of the make in connection with the oxygen of the air in imparting heat to the carbureting-and-fixing chamber until the least-heated portion of the "fixer" (farthest away from the inlet) is of the "critical temperature" for the oil; next, introducing the succeeding make of crude gas, in connection with oil-spray, into this cooler portion as a carbureting-chamber, so as to subject the mixture to the critical temperature; thereafter conducting the mixture through the successive higher temperatures already imparted to the fixing-chamber; and, finally, when the carbureting-chamber has cooled below the critical temperature, reverting to the first step, of heating up the carbureting-and-fixing-chamber,—so that the plant is operated continuously, and without any necessity for reversal or for drawing the fire etc.

The invention will be best understood by describing the novel apparatus for carrying out the novel process, by which is obtained the novel article of manufacture,—viz: fixed carbureted producer-gas.

In the annexed drawings Figure 1 is a side elevation, partly in section, of a preferred plant or apparatus for carrying out the process; and Fig. 2 is a plan of the same.

In these drawings 1 represents a producer, of any standard construction capable of continuous operation, in fact an ordinary blast-furnace may be availed of.

2 indicates a conical hopper, upon which is preferably located a hearth of ashes to support the incandescent fuel.

3 is a charging-device located on top of the producer and having a drop-valve in its bottom and a cover on top.

4 is an outlet from the top of the producer, having the water-cooled valve 5. 6 is a similar outlet from the top of the producer, having water-cooled valve 7, and communicating with down-take passage 8, purge-stack 9, and a water-seal 10, from which latter the conduit 11 leads to the condensers, scrubbers, purifiers, and gas-tank (not shown).

12 is a jet-blower leading to coils 13 within the down-take 8, and thence to the twyer 14 within the base of the producer. An auxiliary jet-blower 15 leading to the same twyer, may be employed.

It will be understood that any approved producer may be employed, but I prefer one of the type indicated.

16 is the "fixer," a cylinder formed of sheet-steel and lined with fire-brick; it comprises a combustion-chamber and a carbureting-chamber with a fixing-chamber between, and there is a continuous passage through all three.

17 represents a perforated arch or dome (or a series of parallel arches) of fire-brick, located near the bottom of the fixer 16. Heat-retainers, preferably a quantity of fire-brick piled up upon this arch *en echelon* or "checkerwise," fill up the interior of the chamber to a point near the top, to constitute the "fixing-chamber" proper,—thus leaving free the combustion-chamber 18 at the bottom and the carbureting-chamber 19 at the top of fixer 16.

20 is a valve-closed purge-stack leading from the top of the fixer 16.

21 and 22 are valve-controlled air-inlets communicating with the chambers 18 and 19 respectively, and operating in connection with air-blowers (not shown), as is well understood.

The up-take pipe 23 leads from the valve-controlled outlet 4 of the producer, to the upper or carbureting-chamber 19. The down-take 8 leads from the other valve-controlled outlet 6 of the producer, and communicates with the lower or combustion-chamber 18. This passage 8 is brick-lined, and of sufficiently large diameter to contain the coils 13 leading from the jet-blower 12, for preheating air or superheating steam or for similar purposes. At the upper end of the down-take 8, the passage 10 branches off to the water-seal; and from the top of passage 8 rises the valve-closed purge-stack 9. The

valve-controlled oil-pipe 24 leads into the elbow at the upper end of the up-take passage 23, and in connection therewith is a suitable steel atomizer (not shown) which discharges an oil-spray, under pressure, into the carbureting-chamber 19. Preferably the oil is preheated in coils 13' within down-take 8.

25 indicates electro-thermostats or other suitable pyrometers for indicating the temperatures.

The operation of the plant comprises first the "firing-up" or starting of the producer, and continuously thereafter the alternating steps of heating-up the fixer 16 and of producing the carbureted gas. The producer may be started up under natural draft by introducing fuel and setting fire to it, leaving the purge-stack 9 open. Or, a forced draft may be created by the jet-blower 12 or by the auxiliary blower 15. When the fuel in the producer has become sufficiently incandescent, and, in the judgment of the attendant, a sufficient output of producer or other crude (that is, uncarbureted) gas is being generated, the apparatus is ready for the heating-up run.

The heating-up run.—Purge-stack 9 and valve 5 (of the up-take 23) are closed, valve 7 (of the down take 8) and purge-stack 20 are opened, and the crude gas passes from the producer, through outlet 6 and down-take passage 8, into combustion-chamber 18, whence the draft will be upward through the piled-up checker-brick and out at stack 20. The air-inlet 22 of the carbureting-chamber 19 remains closed; but air-inlet 21 is opened to admit air to the combustion-chamber 18, where it mingles with the crude gases that are at a temperature of, say, approximately 1000 degrees F. At once combustion takes place, involving a rise of temperature to, say, approximately, 2500 to 3000 degrees F. The products of combustion pass upward, as indicated, and in their upward course the heat is imparted to the checker-brick. It is obvious that the temperature of the lower layers, in immediate contact with the combustion, will rise to 2500 degrees or over; and that, as the products of combustion continue to lose their heat in their upward course, they impart less and less heat to each successive layer of checker-brick; so that the topmost layers of all will be the least heated. This run of heating-up the fixer 16 will be continued until the indication by electrostat 25 is around the highest permissible "critical temperature." For instance, assuming that the "critical temperature" for the particular oil is within the range of 1200 to 1500 degrees F., the run will be discontinued when the thermostat indicates 1500 degrees or thereabout. At this moment the carbureting-chamber 19 will be

of the critical temperature (1500° F.), while 130

the temperature from top to bottom in the fixing-chamber is ever increasing until at the bottom it is nearly 3000° F. It will of course be understood that the temperatures 5 named in this paragraph are approximations only, being given in round numbers merely for the sake of illustration.

Carbureting-run.—To discontinue heating-up and commence carbureting, the 10 purge-stack 9, purge-stack 20, and valve 7 (between the producer and the down-take 8) are all closed, as is the air-inlet 21; and valve 5 (between the producer and the up-take 23) is opened, as is the valve of 15 the oil-pipe 24. It will be recalled that the make of crude gas is being continued without interruption; but, by reason of these changes of the valves, the crude gas now passes upward, through outlet 4 and up-take 20 23, into the carbureting-chamber 19, whence the draft will be downward, and then out and up through the passage 8 and through the water-seal 10 to the gas-tank. The oil-spray being admitted into carbureting- 25 chamber 19 mixes with the crude gas under the influence of the "critical temperature," and the oil is effectively "cracked," and its hydrocarbons carburet the gas. The carbureted gas, in its downward course through 30 the checker-brick, encounters higher and higher temperatures, which properly and most effectively serve to "fix" it; and the fixed carbureted gas is delivered through the water-seal and ultimately to the gas-tank. 35 This carbureting-run is continued until the attendant observes that the temperature of the carbureting-chamber has sunk appreciably below the lowest range of the "critical temperature," when the valves are so moved 40 as to resume the heating-up run. This alteration of the heating-up run and the carbureting-run will be carried on continuously, without interruption, the producer being all 45 while operated continuously by the jet-blower 12, while fresh fuel when needed is admitted through the charger 3. Ashes and clinkers can be removed, by shaking the grate, opening the ash doors, etc., or a 50 change from one kind of fuel to another may be made, without interrupting the operation of the plant.

During the heating-up run the crude 55 gases at high temperature are passing through the passage 8, and during the carbureting-run the fixed carbureted gases at even higher temperatures will be passing upward through the same passage; consequently, the coils 13 and 13' are constantly subjected to these high temperatures for preheating the air and steam and for preheating the oil; and this otherwise waste heat 60 may be made use of in other manners and for other purposes. Moreover, the presence within the wall of down-take 8 of these heat-absorbing coils is valuable in gradually

lowering the temperature of the fixed carbureted gas. This gradual reduction of the temperature of the fixed gases is desirable, since a sudden chilling might cause more or less precipitation and consequent loss of hydrocarbons.

If it be desired that the carbureting-chamber and the upper portion of the checker-brick be heated-up more directly, 75 purge-stack 20 will be closed, the crude gas from the producer will be admitted through up-take 23, and the upper air-inlet 22 opened to admit air for combustion within chamber 19,—the draft being downward and out through passage 8 and purge-stack 9. This will be resorted to when the particular oil employed requires exceptionally high temperature for cracking; so that the fixer 16 will be first heated from chamber 18 and then from chamber 19, before beginning the carbureting run.

By providing a valve-closed passage branching from the uptake 23 to the water-seal, the fixer can be operated upward, upper chamber 19 serving as the combustion-chamber, and oil being introduced into the lower chamber 18 which then becomes the carbureting chamber. In short, the fixer 16 can be used in either direction or in both directions: First, by combustion at the bottom and carbureting at the top; second, combustion at the top followed by carbureting at the bottom; and, third, combustion at the bottom followed by combustion at the top (or vice versa), and then carbureting from the top (or bottom).

Heretofore, the only fixed carbureted gas known is carbureted water-gas; and this is made only from the best grades of anthracite coal; and also coke, etc., have been satisfactorily employed in making straight producer-gas or even straight water-gas. But by my present invention I produce fixed carbureted producer-gas, as a new and highly useful article of manufacture; moreover, by my process any of the fuels may be used effectively and economically in producing first the crude gas, preferably producer-gas, and then producing the fixed carbureted gas valuable for light, heat and power purposes.

The amount of oil admitted will be varied by the operator, according to whether the carbureted-gas is desired for illuminating purposes only or for heat and power purposes only or for all services, as will be well understood. It will likewise be evident that although I have described my invention as a process intended primarily for carbureting producer-gas, it may be employed for carbureting water-gas, although it is most efficient and economical in carbureting producer-gas.

The amount of carbureted producer-gas (in cubic feet) obtained from one ton of the best anthracite coal by means of my present process, is more than four times the amount

of carbureted water-gas obtained from the same quantity and quality of coal by any known process; while its value in B. T. U.'s, volume for volume, is about one-third that of the carbureted water-gas, showing a gain of about 33½% in thermal efficiency in favor of my process, when employing the same high-grade fuel. But my present process can be used effectively and satisfactorily in producing carbureted producer-gas of high quality from inferior fuels that are not used in making either straight or carbureted water-gas. And when my invention is employed with bituminous fuel, less oil for carbureting is needed, since the ever-increasing temperatures encountered in the fixer, recover the volatile elements (distilled from the coal) and properly "fix" them in the gas.

I have described my improved apparatus with some particularity, but only for the sake of clearness, since changes may be made in the construction and arrangement of the parts without departing from the spirit of the invention; and, moreover, my process could be carried out, and my new gas be made, by other apparatus than that herein set forth.

Having thus described my invention, I claim:

1. The method of making carbureted producer-gas from producer-gas and oil, consisting in passing air through a bed of fuel to form producer-gas, igniting the gas and passing the resulting hot products through a fixing chamber, and then subjecting hot producer-gas and oil-vapor commingled therewith to heat in said fixing chamber for the purpose of carbureting and fixing the gas product, and repeating the operations while the air only is continuously passed through the fuel.

2. The method of making carbureted producer-gas from producer-gas and oil, consisting in passing air through a bed of fuel to form producer-gas, igniting the gas and passing the resulting hot products through a fixing chamber, and then subjecting hot producer-gas and oil-vapor commingled therewith to progressively increasing temperatures in said fixing chamber to carburet and fix the gas product, and repeating the operations while the air only is continuously passed through the fuel in one direction.

3. The method of making carbureted producer-gas from producer-gas and oil, consisting in passing air through a bed of fuel to form producer-gas, igniting the gas and passing the resulting hot products through a fixing chamber until the delivery end of the chamber attains a predetermined critical temperature for said oil, and then subjecting hot producer-gas and oil-vapor

commingled therewith to heat in said fixing chamber for the purpose of carbureting and fixing the gas product, and repeating the operations while the air only is continuously passed through the fuel.

4. The method of making carbureted producer-gas from producer-gas and oil, consisting in passing air through a bed of fuel to form producer-gas, igniting the gas and passing the resulting hot products through a fixing chamber, and then subjecting hot producer-gas and oil-vapor commingled therewith to heat in said fixing chamber for the purpose of carbureting and fixing the gas product, then gradually cooling the product, and repeating the operations while the air only is continuously passed through the fuel in one direction.

5. The method of making carbureted producer-gas from producer-gas and oil, consisting in blasting a deep bed of fuel with air to form producer-gas, igniting the gas and passing the resulting hot products through a fixing chamber until the delivery end of the chamber attains a predetermined critical temperature for said oil, then subjecting hot producer-gas and oil-vapor commingled therewith to heat in said fixing chamber for the purpose of carbureting and fixing the gas product, then gradually cooling the product, and repeating the operations while the air only is continuously passed through the fuel.

6. The method of making carbureted producer-gas from producer-gas and oil, consisting in passing air through a bed of fuel to form producer-gas, igniting the gas and passing the resulting hot products through a fixing chamber, then subjecting hot producer-gas and oil-vapor commingled therewith to progressively increasing temperatures in said fixing chamber to carburet and fix the gas product, then gradually cooling the product, and repeating the operations while the air only is continuously passed through the fuel in one direction.

7. The method of making carbureted producer-gas from producer-gas and oil, consisting in blasting a deep bed of fuel with air to form producer-gas, igniting the gas and passing the resulting hot products through a fixing chamber until the delivery end of the chamber attains a predetermined critical temperature for said oil, then subjecting hot producer-gas and oil-vapor commingled therewith to progressively increasing temperatures in said fixing chamber to carburet and fix the gas product, and repeating the operations while the air only is continuously passed through the fuel.

8. The method of making carbureted producer-gas from producer-gas and oil, consisting in blasting a deep bed of fuel with air to form producer-gas, igniting the gas

and passing the resulting hot products through a fixing chamber until the delivery end of the chamber attains a predetermined critical temperature for said oil, then subjecting hot producer-gas and oil-vapor commingled therewith to progressively increasing temperatures in said fixing chamber to carburet and fix the gas product, then gradually cooling the product, and repeating the

operations while the air only is continuously passed through the fuel.

In testimony whereof I have signed this specification in the presence of two subscribing witnesses.
